United States Patent Office.

JOHN RICHARDS, OF PHILADELPHIA, PENNSYLVANIA.

Design No. 4,145, dated June 7, 1870.

DESIGN FOR A BAND-SAW FRAME.

The Schedule referred to in these Letters Patent and making part of the same

I, JOHN RICHARDS, of the city and county of Philadelphia, State of Pennsylvania, have invented and produced a new and original Design for a Band-saw Frame, of which the following is a specification.

The nature of my design is fully represented in the accompanying photographic illustration, to which reference is made, the frame, the design, or configuration of which is new and original, being that portion of the machine marked A, which supports the operative parts of the machine.

Claim.

I claim as my invention—
The design for a band-saw frame, as shown.
In testimony of which invention I hereunto set my hand.

JOHN RICHARDS.
